United States Patent Office.

WILLIAM S. WILDER, OF NEW YORK, N. Y.

Letters Patent No. 79,424, dated June 30, 1868.

IMPROVEMENT IN PAPER-RULING MACHINES.

The Schedule referred to in these Letters Patent and making part of the same.

TO ALL WHOM IT MAY CONCERN:

Be it known that I, WILLIAM S. WILDER, of New York, in the county and State of New York, have invented a new and useful Improvement in Paper-Ruling Machines; and I do hereby declare that the following is a full, clear, and exact description thereof, which will enable those skilled in the art to make and use the same, reference being had to the accompanying drawings, forming part of this specification.

Figure 1 is a vertical longitudinal section of my improved machine, taken through the line $z-z$, fig. 2.

Figure 2 is a top or plan view of the same.

My invention has for its object to furnish a simple, convenient, and accurate paper-ruling machine for ruling bill-heads, &c.; and it consists in the construction and combination of the various parts, as hereinafter more fully described.

A is the frame of the machine, which may be of any convenient shape and size.

B is the main or ruling-cylinder, the journals of which work in bearings attached to the frame A. The cylinder B is revolved by a crank, C, attached to the projecting end of one of its journals, or by any other convenient power.

D is an endless-apron, which passes around the cylinder B, beneath the guide-roller E, placed in front of the cylinder B, and the journals of which revolve in bearings attached to the frame A, and around the guide-roller F, placed in front of the lower part of the cylinder B, and in front of and below the guide-roller E, as shown in fig. 1.

G are endless guide-bands, which pass over the guide-rollers H, pivoted to the upper part of the frame A, down at the rear side of the cylinder B, around the guide-roller I, pivoted to the frame A below the rear part of the cylinder B, thence up and around the upper part of the cylinder B, around the guide-roller E, and thence up to the guide-rollers H, as shown in fig. 1.

J are endless guide-bands, which pass around the guide-roller E, and around the guide and feed-roller K, placed in front of and above the guide-roller F, and the journals of which revolve in bearings in supports L, attached to the cross-bar or beam, a' , of the frame A, as shown in figs. 1 and 2.

By this arrangement of the cylinder, rollers, endless apron, and guide-bands, the paper is conducted over the cylinder B, where it is operated upon and ruled by the pens, as hereinafter described, and then discharged at the lower part of the machine.

M is the apron, from which the paper is fed to the machine, and which is placed in the front part of the machine in a slightly inclined position, and which is provided with guards, m' , one or both of which are adjustable, so that they may be accurately adjusted to the width of the paper, so that the said paper may be conveniently fed in proper position to the machine, into which it is drawn in the manner hereinafter described.

N is a wheel, which revolves loosely upon a gudgeon adjustably attached to the frame A, so that the said wheel may be raised or lowered, as required. The wheel N must be so adjusted that its face may roll along the surface of the cylinder B, from contact with which it receives motion, and it is held down against the face of said cylinder by the action of a coiled or equivalent spring, F', which presses against the upper side of the gudgeon, upon which the said wheel N revolves, as shown in fig. 1.

To the face of the wheel N are adjustably and removably attached cams or lifters O and P, the cams O projecting upon the inner side of the said wheel N, and the cams P projecting upon its outer side.

R is a lever, the rear end of which is adjustably pivoted to a support attached to the frame A, and the forward end of which is connected with the forward side or edge of the pen-beam S, to the lower edge of which the pens should be attached, and the ends of which are pivoted to the frame A.

To the side of the lever R, next the wheel N, is pivoted a friction-wheel, T, under which the cams or lifters O pass and lift or raise the lever R, which rocks the pen-beam S, bringing the pens in contact with the paper, and holding them in contact with it a greater or less time, according to the desired length of the lines or paper to be ruled.

When the lever R is released from the cam O, the pens are lifted from the paper by the spring U, attached to the pen-beam S, and the free end of which rests upon the frame A.

If desired, the lever R may be connected with the rear side or edge of the pen-beam S, so that the pens may be raised from the paper by the action of the cams O, the pens being lowered to the paper by the action of a spring or weight.

V is a lever, pivoted to the frame A, and to the rear end of which is pivoted a friction-wheel, W, so that the said lever may be operated by the cam P attached to the wheel N.

To the forward end of the lever V is pivoted the upper end of the connecting-bar X, the lower end of which rests upon the end of the lever Y, and which may be kept in proper position by passing through a guide attached to the frame A.

The lever Y is pivoted to the frame A, with its forward end beneath the rear edge of the plate or bar Z, which forms a continuation to the apron M, and the ends of which, near its forward edge, are pivoted to the frame A.

A' are guide-arms or springs attached to the plate Z, and extending forward to guide the paper into such a position that it may be seized by the feeding-device.

B' is a stop, one or more of which may be used, and which are attached to supports attached to the frame A in such positions as to stop the advance of the paper at the proper point for it to be grasped by the feeding-device.

C' is a wheel or roller pivoted to an arm or arms attached to the rear edge of the plate Z in such a position that it may be directly beneath the feed-roller K.

In feeding the paper to the machine, the paper is pushed forward against the stop B', as shown in red in fig. 1. Then, as the cam P operates the lever V, the rear edge of the plate Z is raised, lifting the forward edge of the paper above the stop or stops B' until it is grasped between the feed-rollers C' and K. Then, by the movement of the feed-roller K, it is fed forward between the endless apron D and guide-bands J, by the operation of which and the guide-bands G it is carried over the cylinder B, where it is operated upon by the pens.

For ruling continuous lines across the sheet, or from the head-lines to the bottom of the sheet, the wheel N, with its adjustable cams or lifters O and P, is used. This requires different-sized wheels, N, to be used for different-sized paper.

For ruling several bill-heads upon the same sheet, and in other cases where the lines are not continuous, the cams O and P are removed from the wheel N, and themselves or equivalent cams are attached to a belt, D', which passes around the wheel E, the gudgeon of which is adjustably attached to the frame A, so that the said wheel E may be moved further from or nearer to the wheel N, as may be desired.

The belt D' should be so made that it may be lengthened or shortened, according to the size of the paper to be ruled.

It should be observed that the various operating parts of the machine are so constructed and arranged as to be operated automatically by the cylinder B to raise and lower the pens at the proper points as the sheets are fed successively through the machine.

Having thus described my invention, I claim as new, and desire to secure by Letters Patent—

1. The wheel N, having the adjustable and removable cam P, for operating the pivoted feed-plate Z through the medium of the pivoted lever V, carrying the friction-roll W, the connecting-rod X, and pivoted lever Y, all constructed and arranged to operate substantially as herein shown and described.

2. The combination of the wheel N, having one or more adjustable and removable cams or lifters, O P, attached to it, and projecting from each side, the friction-wheel T and lever R with each other and with the cylinder B and pen-beam S, whether said lever R is connected with the front or rear edge of the said pen-beam S, substantially as herein shown and described, and for the purpose set forth.

3. The extension-belt D', adapted for the application to it of the lifters O P, in combination with the adjustable roller E and levers V R, by means of which a sheet may be ruled with lines which are not continuous, substantially as herein shown and described.

The above specification of my invention signed by me, this 25th day of November, 1867.

WM. S. WILDER.
